UNITED STATES PATENT OFFICE

126,863

DESIGN FOR A RADIO-PHONOGRAPH CABINET

Edgar F. Haines, Philadelphia, Pa., assignor to
Philco Radio and Television Corporation, Phila-
delphia, Pa., a corporation of Delaware

Application January 31, 1941, Serial No. 98,625

Term of patent 14 years

To all whom it may concern:

Be it known that I, Edgar F. Haines, a citizen
of the United States, residing in Philadelphia,
Philadelphia County, Pennsylvania, have in-
vented a new, original, and ornamental Design
for a Radio-Phonograph Cabinet, of which the
following is a specification, reference being had
to the accompanying drawings, forming part
thereof, in which:

Fig. 1 is a perspective view of a radio-phono-
graph cabinet showing my design; and

Fig. 2 is a different perspective view of the
cabinet as it appears in open condition for access
to the phonograph.

I claim:

The ornamental design for a radio-pheno-
graph cabinet, substantially as shown.

EDGAR F. HAINES.
